(52) **U.S. Cl.**

The ornamental design for an extended handle circular saw, as shown and described.

USPC **D8/70**; D8/66

DESCRIPTION

(58) **Field of Classification Search**

FIG. 1 is an isometric view of an extended handle circular saw embodying my design;

USPC D8/61, 66, 67, 68, 69, 70, 107, 303

FIG. 2 is a side view of the extended handle circular saw; FIG. 3 is a side view of the extended handle circular saw; FIG. 4 is a top plan view of the extended handle circular saw;

CPC B27B 9/00; B27B 9/02; B27B 5/18; B27B

FIG. 5 is a bottom plan view of the extended handle circular saw;

33/08; Y10T 16/461; Y10T 16/4713;

FIG. 6 is a front view of the extended handle circular saw; FIG. 7 is a back view of the extended handle circular saw; and,

B25G 1/04

FIG. 8 is an isometric view of an extended handle circular saw in a position of use.

See application file for complete search history.

The saw depicted by broken lines in FIG. 8 have been shown for the purpose of illustrating environmental features that form no part of the claimed design.
